UNITED STATES PATENT OFFICE.

JOHN MRAZEK, OF CHICAGO, ILLINOIS.

SIGN-LETTER.

949,155.

Specification of Letters Patent. Patented Feb. 15, 1910.

Application filed August 16, 1909. Serial No. 513,049.

To all whom it may concern:

Be it known that I, JOHN MRAZEK, a citizen of the United States, residing at Chicago, county of Cook, and State of Illinois, have invented certain new and useful Improvements in Sign-Letters, of which the following is a specification.

My invention relates to improvements in sign letters, the main object of the invention 10 being to provide suitable means for securing transparent ornamental inlays in a letter of this character.

A further object of my invention is to provide adequate means for protecting the 15 inlays from the weather when the same are silvered to form mirrors thereof.

Other objects will appear hereinafter.

With these objects in view my invention 20 consists in the novel construction and arrangement of parts which will be herein-after fully described and more particularly pointed out in the appended claims.

My invention will be more readily understood by reference to the accompanying 25 drawing forming a part of this specification, and in which,

Figure 1 is a front elevation of my improved sign letter, showing the same attached to a sign board, Fig. 2 is a transverse section taken through the letter and one of the ornamental inlays secured therein, Fig. 3 is a section similar to Fig. 2 but showing an inlay in elevation, and Fig. 4 is a transverse section showing a recess or depression 35 in which an inlay is secured.

Referring now to the drawings, 1 designates a sign board and 2 a letter of my improved construction attached thereto. Formed in the letter 2 are a plurality of 40 hemispherical recesses or cavities 3 as shown in Fig. 4. Substantially hemispherical transparent ornamental inlays 5 are provided, the same having preferably a series of facets 6 cut on the curved portions thereof. These facets are silvered in order that each inlay may produce a brilliant effect by reflecting light.

In order to secure each inlay 5 in its recess 3, the recess is first partially filled with 50 cement 7 in a plastic condition, then the inlay is forced therein until it becomes on a level with the surface of the letter. The

cement is smoothed off flush with the surface of the inlay and the letter, and when the same becomes set the inlay is rigidly 55 secured therein. Owing to the adherence of the cement 7 to the silvered portion 8, the latter will not be affected by the weather, consequently the facets will always reflect light perfectly and present a brilliant and 60 dazzling appearance.

The letters are formed preferably of wood but any other material which the cement will readily adhere to may be employed. The inlays may be colored glass, cut crystal, 65 or other like substances. Where it is desired to produce a color effect the letters may be colored or tinted, and the inlays be formed of colored glass to match the color of the letter. The facets of the inlays are 70 preferably cut or ground but may be molded in the glass, it being understood that the size and the design of the facets may be varied to suit the taste or any particular design of letter.

Various changes might be made in the general form and arrangement of parts described without departing from my invention, and hence I do not restrict myself to the precise details set forth, but consider 80 myself at liberty to make such changes and alterations as fairly fall within the spirit and scope of the appended claims.

Having described my invention what I claim as new and desire to secure by Letters 85 Patent is:

1. A sign letter comprising a body having recesses therein and a transparent inlay having mirrored facets on its inner surface, the said inlay being embedded in and having its 90 mirrored facets completely covered by cement, substantially as described.

2. A sign letter having a series of hemispherical recesses formed therein, a layer of cement in each of said depressions, and a 95 substantially hemispherical transparent inlay having facets formed on its substantially curved surface secured in each recess, the facets being silvered to form mirrors of said inlays, substantially as described.

3. A wood sign letter having a plurality of hemispherical recesses formed therein, a layer of cement in each recess, a substantially hemispherical transparent inlay se-

cured in the cement of each recess, the layer
of cement in each recess being of a uniform
thickness, and a series of facets cut in curved
surface of each inlay, said facets being sil-
vered and adjacent the layer of cement in
each recess, substantially as described.

In testimony whereof I have signed my

name to this specification in the presence of
two subscribing witnesses.

JOHN MRAZEK.
